SUPPORT FOR ELECTRIC APPLIANCE

Filed Oct. 29, 1949

UNITED STATES PATENT OFFICE

2,691,498

SUPPORT FOR ELECTRIC APPLIANCE

Donald F. McCarron, St. Louis, Mo., assignor to
 Knapp-Monarch Company, St. Louis, Mo., a
 corporation of Delaware

Application October 29, 1949, Serial No. 124,327

2 Claims. (Cl. 248—13)

1

This invention relates to a support for an electrical appliance and particularly a handle for a hair dryer or the like in which handle the hair dryer or other appliance is rotatably mounted for adjustment to various angles.

One object of the invention is to provide a simple connection between a handle and an appliance for the adjustment just referred to so that when the support is used in connection with a hair dryer, for instance, the discharge nozzle may be pointed upwardly or downwardly at a desired angle, the handle also having a bore to rotatably receive a pin on a supporting base so that the appliance can be turned for directing the nozzle at various angles in a horizontal plane.

Another object is to provide a handle structure with a novel type of connection between the handle and an appliance such as one having an electric motor, said connection consisting of a C-shaped spring adapted to partially encircle the motor and permit rotation of the motor therein for adjusting the angle of a discharge nozzle or the like carried by the motor housing without the necessity of providing pivot connections, clamp screws therefor and the like, the handle being specially constructed for cooperation with a novel type of connection between it and the C-shaped spring.

With these and other objects in view, my invention consists in the construction, arrangement and combination of the various parts of my support for electric appliance, whereby the objects contemplated are attained, as hereinafter more fully set forth, pointed out in my claims and illustrated in the accompanying drawings, wherein:

Figure 1 is a side elevation of a support embodying my invention and including a handle, a hair dryer being shown supported thereby, the hair dryer having a discharge nozzle shown directed downwardly at a slight angle in solid lines and upwardly at a slight angle in dotted lines, the handle and dryer being mounted on a supporting base which is also part of the support.

Figure 2 is a perspective view of the handle per se with the hair dryer removed.

Figure 3 is a plan view of Figure 1.

Figure 4 is a vertical sectional view on the line 4—4 of Figure 3; and

Figure 5 is an enlarged end elevation of the upper end of the handle.

On the accompanying drawing I have used the reference character B to indicate a base, H a handle, and M a motor. The base B may be molded of suitable plastic material such as Bake-

2

elite and has an opening 10 formed therein to receive a shouldered pin 12. The shoulder of the pin fits against a sheet metal reinforcement 14 countersunk in the upper surface of the base B and is threaded at its lower end for a lock nut 16 for mounting the pin rigidly with respect to the base.

The handle H may also be molded of Bakelite or the like and has a bore 18 to rotatably receive the pin 12. The upper end of the bore 18 terminates in a shoulder 20 for the head 22 of a tie bolt 24, the purpose of which will hereinafter appear.

Adjacent the upper end of the handle H, internal ribs 26 are provided and a pair of locating projections 28 are provided projecting inwardly from each side wall of the handle as shown in Figure 5. The ribs 26 between the projections 28 support a rectangular piece of sheet metal 30 having a hole 32 therein to receive the bolt 24.

Seated on the sheet metal 30 is a C-spring C which has a pair of offsets 34 and 36 connected by a cross piece 38 which is also perforated to receive the screw 24. A washer 40 above the cross piece 38 is positioned on the screw 24 and a lock nut 42 completes the assembly so that the C-spring is rigidly connected to the handle H when the screw is tightened with respect to the nut.

When the C-spring is seated against the sheet metal 30, its arms are seated against upper edges 43 and 44 of the handle to provide a type of support that prevents any wobbling of the C-spring relative to the handle.

The arms of the C-spring are lined with strips of felt 46 cemented to the arms and the arms are sprung from the full-line position of Figure 2 to the dotted position thereof around the housing 47 for the motor M as shown in Figures 3 and 4 for supporting the motor and its housing. The housing is usually plated and polished and the felt prevents scratching it.

The motor housing 47 preferably has a pair of beads 48 therearound to position the C-spring with respect to the housing.

The housing illustrated terminates in an air discharge nozzle 50 and the housing encloses the motor M which motor is for driving a fan (not shown) as is usual construction in small handheld hair dryers of the type disclosed. The base B is then provided so that the hair dryer can be placed on a dresser or the like and by the two adjustments (1) in the vertical plane by rotating the motor housing 47 in the C-spring, and (2) in the horizontal plane by rotating the handle H on the pin 12, various desired adjustments can

be had for directing the nozzle 50 at the desired angle.

The type of connection between the handle and the motor housing disclosed is very simple and inexpensive to manufacture and gives all adjustments required anywhere throughout a 360 degree circle in the vertical plane. The same is true with respect to the handle H in the horizontal plane. In its adjustment about the pin 12, for instance, the hair dryer may be placed on a foot stool or on the floor and the handle H turned a half turn in Figure 1 whereupon the discharge nozzle can be directed upwardly at a relatively sharp angle if this type of adjustment is indicated.

Some changes may be made in the construction and arrangement of the parts of my support for electric appliance without departing from the real spirit and purpose of my invention, and it is my intention to cover by my claims any modified forms of structure or use of mechanical equivalents which may be reasonably included within their scope.

I claim as my invention:

1. In a support for a hand-held or base-supported electrical appliance, a handle member having a socket in the upper end provided with a bottom, said bottom being located adjacent the peripheral edge of said upper end, a C-shaped spring having its central portion located in said socket and rigidly connected with said handle against said bottom, the arms of said C-shaped spring being seated at their lower portions against the upper peripheral edge of said handle, said spring having its arms partially surrounding a substantial cylindrical portion of the appliance and frictionally retaining the same relative to said handle member, said cylindrical portion being slidably rotatable in said arms, said arms being

ing lined with non-metallic material, said handle having a bore in its lower end, and a base having a pin projecting upwardly into said bore for rotatably supporting said handle.

- 5 2. In a supporting structure for a hand-held or base-supported electrical appliance, a handle, ribs formed therein, a cross-piece supported on said ribs, a C-shaped spring seated on said cross-piece, a tie bolt in said handle for holding said C-shaped spring rigidly against said cross-piece and said cross-piece rigidly against said ribs, said cross-piece and supporting ribs being located adjacent the upper end of said handle whereby the arms of said C-shaped spring seat at their lower portions against the upper edge of said handle, the bore for the head of said tie bolt being adapted to receive a pin projecting upwardly into the lower end of said handle from a supporting base, and the arms of said C-shaped spring being lined with resilient material and adapted to partially surround and frictionally engage a cylindrical portion of an appliance, said cylindrical portion being slidably rotatable in said arms.
